SWELL CONTROL

Thomas B. Gibbs, Delavan, and William H. Krug, Janesville, Wis., assignors to Gibbs Manufacturing & Research Corporation, a corporation of Wisconsin

Filed Dec. 14, 1959, Ser. No. 859,424

2 Claims. (Cl. 84—1.27)

This invention relates to a swell control for an electronic musical instrument and more particularly with an improved electronic swell control circuit.

In an electronic musical instrument, as an electronic organ, it is undesirable to use a simple voltage divider or potentiometer to control the volume of the ultimate signal from the system as such elements introduce noise, are subject to wear, and in many cases must be specially manufactured to maintain a desired relationship of volume level to the deflection or other actuation of a control member. A swell control has been proposed in which a variable impedance device, as a vacuum tube, is shunted across the signal channel of the audio amplifier and its impedance is manually varied, as by varying the light shining on a photoelectric cell connected with the control tube. The variation in the shunt impedance presented to the signal channel causes a resulting change in the amplitude of the audio signal. It has been found, however, that control results in a shift of the D.C. potential of the anode of the vacuum tube which is coupled from the variable impedance element to the signal channel with resultant interference in the nature of an audio frequency superimposed upon the signal.

A principal object of this invention is the provision in the swell control circuit of a variable impedance element that compensates for the effect of D.C. anode potential shift of the swell control circuit and the resultant audible disturbance to the signal.

One feature of the invention is that the variable impedance element is connected in the anode circuit of the control tube and essentially forms a parallel path connected in shunt with the control tube, compensating for D.C. anode potential shift of the control tube.

Another feature is the provision in the circuit of a feedback network which cancels hum from the control tube at low swell levels. A further feature is that the control tube is responsive to a photoelectric cell connected in the grid circuit thereof with a capacitor connected in the photocell circuit, eliminating high frequency interference.

Further features and advantages of the invention will readily be apparent from the following specification and from the drawings, in which:

FIGURE 1 is a block diagram of a musical instrument system; and

FIGURE 2 is a schematic circuit diagram of an embodiment of the invention.

In certain electronic musical instruments the control of the volume of the produced tones is extremely important in determining the quality of the instrument. For example, in an electronic organ, the swell control must correspond accurately in operation with the operation of the swell control in a pipe organ, having a specific relation between the angular deflection of the swell control pedal and the acoustic level of the generated tones. It is desirable to eliminate from such a circuit any physically variable element as a variable resistor or potentiometer, in which it is difficult to control the exact operating characteristics and which has a tendency to wear unevenly and change characteristics with age, and to introduce noise interference in the circuit. This is done in various circuits utilizing a variable impedance control tube connected with the signal channel. However, as

2

outlined above, merely substituting a variable impedance tube for a potentiometer is not the whole solution of the problem. In certain circuits of the aforementioned application, the variable plate resistance of the tube is essentially connected in parallel with the plate dropping or load resistor, shunted across the signal channel. A certain portion of the audio signal in the signal channel is coupled to the swell control tube resulting in a variation of the tube plate resistance at an audio rate, and a corresponding variation in the voltage level at the plate. This in effect amounts to a distortion of the audio signal with a resultant high frequency variation in the signal level which is objectionable. The circuit of the present invention eliminates this problem by shunting the variable impedance tube with an element which has a resistance variation in response to the signal voltage that compensates for the change of the plate resistance of the tube.

In FIGURE 1 the basic elements of an electronic musical instrument are illustrated in block form. A tone generator 10 produces or generates electrical signals corresponding with the desired musical tone and may for example utilize a light scanning system. The tone representing signal is transmitted through a signal channel 11 to an amplifier 12 which has a suitable speaker system 13 connected with its output. Connected in shunt with signal channel 11 is a swell control 14 which effectively varies the amplitude of the signal and thus controls the volume of the sound from speaker system 13.

A specific embodiment of the invention will be described in connection with the schematic circuit of FIGURE 2 and values and types will be assigned to the various elements of the circuit. It will be understood that this specific circuit is intended to illustrate an operative embodiment of the invention and that many changes and modifications may be made by those skilled in the art.

The output of tone generator 10, which comprises an electrical signal representing the desired musical tones, is coupled through capacitor 18, 0.01 μ f., to the control grid of an amplifier 19, one-half of a 12AX7 dual triode. The control grid is returned to a reference potential or ground 20 through resistor 21, 470,000 ohms; and the cathode circuit includes an unbypassed bias resistor 22, 2700 ohms. The plate of amplifier 19 is connected through anode load resistor 23, 330,000 ohms, with a source 24, of positive potential. The amplified tone representing signal from amplifier 19 is connected through a parallel resistance-capacitance circuit including resistor 25, 1 megohm, shunted by capacitor 26, 0.00047 μ f., forming a part of the signal handling channel 11.

Swell control 14 includes a triode 29, one-half of a 12AT7, connected in shunt with signal handling channel 11 through capacitor 30, 0.05 μ f. A positive bias is applied to the cathode of variable impedance tube 29 through a voltage divider connected with positive source 24 including resistor 31, 150,000 ohms, connected in series with potentiometer 32, 15,000 ohms, connected between the cathode and ground 20. Potentiometer 32 is shunted by capacitor 33, 4.0 μ f. With no signal applied to the grid of variable impedance tube 29, it is for all practical purposes cut off and presents a high impedance to signal channel 11. The grid circuit includes a pair of resistors 34, 680,000 ohms, and 35, 1 megohm, connected in series and returned to ground 20. A manually operable swell control is provided by a photoelectric cell 36 which has its plate connected with positive source 24 and its cathode returned to ground through resistor 35 in the circuit of the control grid of variable impedance tube 29. Light from lamp 37 is directed past a mask member 38 mounted to swell pedal 39 to the cathode of photoelectric cell 36. With full light shining on the photocell

it conducts heavily, applying a positive potential to the control grid of variable impedance tube 29 reducing its impedance and establishing a condition of low swell or minimum volume. As pedal 39 is depressed mask 38 progressively cuts off more and more of the light from lamp 37 directed toward photocell 36 reducing the current flow through the photocell and thus reducing the positive potential applied to the control grid of variable impedance tube 29. With the light fully masked, there is no conduction through the photocell and the impedance of tube 29 is a maximum, corresponding with the condition of full swell in the instrument.

As pointed out above a portion of the tone representing signal in signal channel 11 is coupled through capacitor 39 to the plate of variable impedance tube 29. This audio signal at the plate tends to cause the current through tube 29 and thus the impedance thereof to vary at the rate of the audio signal resulting in an undesired distortion in the signal channel.

In order to eliminate this condition, the plate circuit of variable impedance tube 29 includes an element 42 the resistance of which varies inversely with the voltage applied to it, as a variable resistor element of a silicon carbide material, manufactured and sold by General Electric under the trademark Thyrite Varistor. For an analysis of the alternating current operation of the circuit, the plate circuit impedance element 42 may be considered as paralleling the plate resistance of the variable impedance tube 29. It will be seen that when the signal voltage at the plate of tube 29 goes positive the current flowing through the tube increases, causing an apparent decrease in the plate resistance. At the same time, the resistance of variable impedance element 42 increases, as a result of the decreased voltage across it when the audio signal increases toward the positive potential of B supply 24. Accordingly, the change in the impedance of the plate circuit elements compensates for the change in the plate resistance of the variable impedance tube and the entire shunt circuit presents a substantially constant impedance to the signal channel. When the audio signal voltage goes negative, the operation is reversed, the plate resistance of tube 29 increasing and the resistance of variable element 42 decreasing. A resistor 43, 470,000 ohms, is connected in shunt with variable impedance element 42 and their relative values are such that the parallel combination closely approximates an inverse exponential resistance relationship with the plate resistance of tube 29. The variable impedance element 42 has characteristics such that its resistance may cover the range from 20,000 ohms to 2 megohms, for the circuit described herein.

The substantial elimination of the effect of distortion of the audio signal in the variable impedance circuit permits the use of a feedback capacitor 44 connected between the plate and control grid of tube 29 which has sufficient capacity to eliminate substantially all hum and noise developed within the tube 29. Specifically, this capacitor has been increased from 0.002 μ f. to a value of 0.007 μ f.

Furthermore, capacitor 45, 0.02 μ f., is connected across

one megohm resistor 35 in the circuit of photocell 36. This reduces any interference from low frequency current variations in the photocell circuit, or hum pickup from the interconnecting cables.

5 While we have shown and described certain embodiments of our invention, it is to be understood that it is capable of many modifications. Changes therefore, in the construction and arrangement may be made without departing from the spirit and scope of the invention as disclosed in the appended claims.

We claim:

1. In an electronic musical instrument having a source of tone representing signals and a signal handling channel connected to a source of potential, swell control means comprising: a circuit including a variable impedance electron tube having a plate circuit and a grid circuit having a bias potential applied thereto; a first reactive element coupling said plate circuit to said signal channel, a second reactive element coupling said grid circuit to the junction of said plate circuit and said first reactive element; manual control means for effecting a change in the bias voltage applied to said grid for affecting the impedance of said tube to vary the level of the signal in said channel; and a variable impedance element connected to said plate circuit at said junction and to said source of potential whereby it is in partial shunt with said first reactive element and said signal channel, said variable impedance element having an impedance which varies inversely with the voltage applied thereto for preventing signal changes in said channel from affecting the output of said tube.

2. In an electronic musical instrument having a source of tone representing signals and a signal handling channel connected through a first resistance element to a source of potential, swell control means comprising: a circuit including a variable impedance electron tube having a plate circuit and a grid circuit having a bias potential applied thereto; a first capacitor connecting said plate circuit to said signal channel; a second capacitor connecting said grid circuit to said plate circuit at the junction of said plate circuit with said first capacitor; manual control means for effecting a change in the bias on said grid circuit of said tube to vary the level of the signal in said channel; and a voltage sensitive resistance element whose resistance varies inversely with voltage connected at said junction and between said plate circuit and said source of potential in shunt with said first capacitor and said first resistance element to prevent changes in signal level appearing in said channel from affecting said tube.
